F. B. ADAM.
FAN HANGER OUTLET.
APPLICATION FILED APR. 27, 1916.

1,244,454.

Patented Oct. 30, 1917.

Inventor,
Frederick B. Adam.
By Bakewell & Neckatt, Atty's.

UNITED STATES PATENT OFFICE.

FREDRICK B. ADAM, OF ST. LOUIS, MISSOURI, ASSIGNOR TO FRANK ADAM ELECTRIC COMPANY, OF ST. LOUIS, MISSOURI, A CORPORATION OF MISSOURI.

FAN-HANGER OUTLET.

1,244,454.

Specification of Letters Patent. Patented Oct. 30, 1917.

Application filed April 27, 1916. Serial No. 94,010.

To all whom it may concern:

Be it known that I, FREDRICK B. ADAM, a citizen of the United States, residing at St. Louis, Missouri, have invented a certain 5 new and useful Improvement in Fan-Hanger Outlets, of which the following is a full, clear, and exact description, such as will enable others skilled in the art to which it appertains to make and use the same.

10 This invention relates to devices that are used to support or house a socket in which a plug or other form of connector is adapted to be arranged so as to connect an electrically-operated device to an electric circuit.

15 Prior to my invention electric fans were either mounted on a table or on a bracket, shelf or wall plate secured to a wall in proximity to the connecting receptacle for the fan. The methods above referred to for supporting electric fans are all more or less unsatisfactory, on account of the space they take up and the unsightly appearance they present, both when the fan is in use and 25 after the fan has been put away for the season.

20 The main object of my invention is to provide a combined receptacle carrier and fan hanger that presents a neat and ornamental appearance at all times, thus overcoming the necessity of mounting a bracket, shelf, plate or other device on a wall, in addition to the receptacle carrier, for supporting a fan that is in use.

30 35 Another object is to provide a fan hanger outlet which is so designed that an electric fan can be installed on same or removed from same quickly and easily.

40 And still another object is to provide a supporting device for an electrical receptacle, which comprises as a part thereof a means for securely supporting a fan in such a position that the fan will give the best service to the entire room.

45 Figure 1 of the drawings is a perspective view, illustrating one form of my improved fan hanger outlet arranged in operative position in a wall, with a fan and its connector in operative position.

50 Fig. 2 is an enlarged vertical sectional view of said device;

Figs. 3 and 4 are detail sectional views, illustrating slight modifications of my invention; and

55 Fig. 5 is a perspective view, illustrating

another form of my improved fan hanger outlet.

Referring to Figs. 1 and 2 of the drawings, which illustrate one form of my invention wherein the receptacle carrier is in 60 the form of an outlet box, A designates the body portion of the outlet box that forms a housing for an electrical receptacle 1, and 2 designates the removable cover of the box which preferably consists of a metal plate 65 that is detachably connected to the body portion A by means of screws or other suitable fastening devices 3 that are screwed into elements 4 formed either by integral lugs on the body portion of the box, or by 70 separate members arranged at the four corners of said body portion, or in any other suitable position, and securely connected to the body portion by brazing, riveting or in any other suitable manner. The 75 cover 2 completely hides the body portion of the box from view, and said cover is provided with an opening through which a plug 5 or other form of connector can be inserted, so as to establish electrical connection between an electrically-operated device, such, for example, as a fan B, and the electric wires 6 that lead to the receptacle 1 arranged inside of the box, as shown in Fig. 2. When the plug or connector 5 is not 80 mounted in the receptacle 1, the opening in the cover 2 through which said plug passes is covered by a closure 7 which is preferably hinged to the cover 2.

85 The outlet box above described comprises 90 as a permanent part thereof a fan hanger or supporting device for the fan B that is connected to the receptacle arranged inside of the box. Said fan hanger or supporting device may be formed in various ways and 95 can be combined with the box in various ways without departing from the spirit of my invention. In the form of my invention illustrated in Figs. 1 and 2 the fan hanger consists of a device 8 carried by the cover 2 100 of the outlet box and projecting forwardly from the lower portion of said cover so as to form a projection on the box on which the base plate 9 of the fan can be hung, as shown in Figs. 1 and 2. The device 8 may 105 either consist of a bolt arranged with its head 8^a on the inside of the cover 2 and its screw-threaded shank projecting forwardly through the cover and securely connected to the cover in any suitable manner, such, for 110

example, as by soldering or brazing the head 8^a to the inside face of the cover 2, or said device may consist of a bolt 80 whose head 80^a is arranged on the outside of the 5 cover 2, and whose shank is screwed into a nut or block 80^b permanently connected to the inner face of the cover 2, as shown in Fig. 3. With a hanger of the form shown in Fig. 2 the base plate of the fan can be 10 slipped over the forwardly-projecting shank of the hanger and then locked securely in position by screwing a nut 8^b onto said shank. With a hanger of the form shown in Fig. 3 the base plate of the fan can be 15 placed against the cover 2 and the bolt 80 can thereafter be inserted through a hole in said base plate and screwed into the nut 80^b on the inside of the cover 2 of the outlet box. When the fan is not arranged in op- 20 erative position on the box the bolt 80 can be screwed inwardly into the position shown in broken lines in Fig. 3, so that only the head 80^a will be exposed to view.

It is immaterial, so far as my broad idea 25 is concerned, whether the fan hanger is carried by the cover 2 of the box or by the body portion A of the box. In Fig. 4 of the drawings I have illustrated a form of my invention wherein the hanger is perma- 30 nently connected to the body portion A of the box, said hanger consisting of an externally screw-threaded stud 180 that projects forwardly through an opening in the cover 2 of the box. The stud 180 can be 35 connected to the body portion of the box in various ways, but it is preferably connected to a post or block 10 that is riveted or connected in any other suitable manner to the body portion of the box, said stud 40 being provided with a nut 180^a that is adapted to be moved into engagement with the base plate of the fan mounted on the stud.

It is also immaterial, so far as my broad idea is concerned, whether the receptacle is 45 carried by an outlet box embedded in the wall, or by a plate or other member secured to the face of the wall. In the form of my invention illustrated in Fig. 5 the receptacle carrier consists of a wall member, 50 preferably a plate A' that is adapted to be arranged on the face of a wall, said wall member being provided with an electrical receptacle 1^a, mounted either directly on said member or in any other preferred 55 manner. At a point preferably below said receptacle, a fan hanger 280 projects forwardly from the plate A', said fan hanger consisting of a fixed bolt, as shown in Fig. 2, a removable bolt, as shown in Fig. 3, or 60 any other suitable means that will serve as a support for an electric fan.

A structure of the character above described forms a combined electrical outlet

and fan hanger that presents a neat and ornamental appearance at all times. When 65 the fan is in use the base plate of the fan bears against the portion of the receptacle carrier that is arranged on the face of the wall, and the only portion of the hanger that is exposed to view is the nut on the 70 shank of the hanger in the form of my invention shown in Figs. 2, 4 and 5, or the head on the shank of the hanger in the form of my invention shown in Fig. 3. When the fan is not in use the receptacle carrier 75 presents the same appearance as an ordinary wall receptacle carrier, except that a small stud or screw or a bolt head projects forwardly from the lower portion of the carrier. A fan can be attached easily to a structure of the character above described or can be disconnected from same easily by simply manipulating a single nut or a single bolt, depending upon whether the hanger is in the form of a stationary bolt or a removable bolt. Furthermore, when the fan is 80 not in use the receptacle can be used for establishing connection between any other electrically-operated device and the circuit in which the receptacle is arranged. A fan 90 hanger outlet of the construction above described overcomes the necessity of marring a wall by attaching a shelf, bracket, wall plate or other device to the wall, in addition to the receptacle carrier, to support the fan 95 when the fan is in use; it presents practically the same appearance as an ordinary wall receptacle carrier when the fan is not in use and in view of the fact that it is intended to be arranged on a side wall, some 100 distance above the floor, it supports the fan in such a position as to give the best service to the entire room.

Having thus described my invention, what I claim, and desire to secure by Letters Patent, is:

A fan hanger outlet, consisting of a box that is adapted to be set in a side wall so as to form a housing for an electrical receptacle or similar element connected to a supply circuit, a cover for said box, a rugged device projecting forwardly from said cover so as to form a support for an electric fan which is adapted to be removably mounted on said device, and means for securely 110 clamping the base of the fan against said cover, said cover having an opening in same through which the connector of the fan can be inserted.

In testimony whereof I hereunto affix my 120 signature in the presence of two witnesses, this twenty-fourth day of April, 1916.

FREDRICK B. ADAM.
